(57) **CLAIM**

The ornamental design for a firearm, as shown and described.

DESCRIPTION

FIG. 1 is a perspective view of a firearm showing our new design;

FIG. 2 is a top elevation view thereof;

FIG. 3 is a bottom elevation view thereof;

FIG. 4 is a left elevation view thereof;

FIG. 5 is a right elevation view thereof;

FIG. 6 is a front elevation view thereof; and,

FIG. 7 is a rear elevation view thereof.

The broken lines in the figures are for the purpose of illustrating environmental structure only and form no part of the claimed design.
